UNITED STATES PATENT OFFICE.

JOHN N. HAHN, OF CLEVELAND, OHIO.

REINFORCING CONTRIVANCE.

1,264,877.

Specification of Letters Patent. Patented Apr. 30, 1918.

Application filed March 8, 1915. Serial No. 12,887.

To all whom it may concern:

Be it known that I, JOHN N. HAHN, a citizen of the United States, residing at Cleveland, in the county of Cuyahoga and

- 5 State of Ohio, have invented a new and useful Improvement in Reinforcing Contrivances, of which the following is a specification, the principle of the invention being herein explained and the best mode in which
10 I have contemplated applying that principle, so as to distinguish it from other inventions.

This invention in reinforcing contrivances appertains more particularly for the exemplifying purpose in hand to a metal strip for use in enveloping and binding boxes or the like.

Heretofore, in so far as I am aware, it has been customary to apply and affix what 20 is commonly termed as "strap iron" by first conforming it to the contour of the box and thereafter securing either with nails or with separate staples which were later usually clenched interiorly. This mode has been 25 clumsy, laborious and wasteful of both time and material, besides presenting a crude appearance.

Accordingly the objects of my invention are:

30 (1) To provide "strap iron" which while simple, sightly and economical of manufacture is moreover easier to apply and commercially more efficient.

(2) To provide a packing accessory of 35 the character stated which obviates the need for either staples or nails.

(3) To provide a unitary securing agency which, in the case of fiber or pulp board, may be tightly and neatly affixed indeed 40 locked in a single machine operation.

(4) To provide a limited reinforcement therefor such that a predetermined thickness of the box material is penetrated and effectively clenched.

45 In the fulfilment of the last mentioned object the principle shown, described and claimed in United States Letters Patent No. 951,393 issued to me on March 8, 1910, is effectively utilized here.

50 The inventive conception is associated with elements which are hereinafter explained and variously combined in the claims. While the annexed drawing and particular description thereof set forth the 55 preferred form embodying my invention, it should be understood that the means

merely exemplify many diversified mechanical forms with which the principle of my invention may be properly applied.

Adverting to the drawings in which like 60 characters of reference consistently designate like parts throughout:

Figure I is a perspective view of a fiber board box showing my invention associated therewith.

Fig. II is a plan of a flat stock sheet of fiber board showing a number of strap irons scored up in intimate association therewith.

Fig. III is a perspective view of that length of reinforced sheet which is shown in 70 Fig. II after the same has been formed to the shape of the box desired.

Fig. IV is a perspective view of another detail.

Fig. V is an enlarged top plan of strip of 75 strap iron embodying my invention.

Fig. VI is a longitudinal section of Fig. V.

Fig. VII is a longitudinal section showing the manner in which my invention becomes 80 clenched to the board.

Fig. VIII is a section of line VIII—VIII of Fig. VI looking in the direction of the arrows.

Fig. IX is a bottom plan view of line 85 IX—IX of Fig. VII.

Fig. X is a view corresponding to Fig. VIII, slightly modified.

Fig. XI is a top plan of a portion of a strip of strap iron involving a different 90 modification.

Figs. XII and XIII are cross sections and longitudinal sections respectively taken on the lines indicated.

Figs. XIV and XV are views corresponding 95 to Figs. XI and XIII of still another modification.

Fig. XVI is an enlarged perspective view of a corner of a completed box, showing the manner in which opposite ends of a binding 100 strip may become fixed relatively to each other.

I have elected as well adapted to illustrate the manner of use of my invention a new type of fruit crate including in its structure both wood and pulp composition or fiber strips, the whole if desired to be reinforced and bound together solely by my inventive improvement. The wood employed in the type of box shown consists quite arbitrarily of three similar equispaced frames 110 each of which is covered on one side by a

piece of fiber material 2 whereby the frames when thus closed serve as end walls, and an intermediate partition for the completed box. A sheet of fiber board 3 suitably cut 5 to size is in this instance reinforced by three strips of strap iron 4 which are affixed, and moreover clenched along the longitudinal edges and the middle thereof in a manner to be presently fully described. It should be 10 understood that the term "board" as used in this application refers to and may mean any kind of material including fiber board, straw board, veneer board and wooden board of whatsoever width, length, thickness 15 or area. As so applied the straps 4 are similarly spaced as the frames 1, and their arrangement may be similarly varied at will. Each of the metal straps embodying my invention is provided along its longitudinal middle with a series of upwardly 20 projecting corrugations or stiffening ribs 5 separated by comparatively short distances of flat material. They are furthermore fashioned at intervals corresponding with 25 the spacing between the stiffening ribs 5 with a plurality of similarly projecting struck-out tongues 6. The formation and arrangement of the tongues 6 is such that each includes in its structure a portion of 30 one of the ribs 5, and substantially all of that flat middle portion of the strap which was between two adjacent ribs 5. The particular construction or finished contour of the tongues 6 is clearly shown in 35 Figs. VI and VIII, to include a flat point 7 and an upper portion stiffened by a medial rib 8 which originally formed one end of one of the ribs 5. I have discovered that by 40 employing a female die slightly larger than the male die, the corner portions constituting the junction of the tongues with the strap becomes indented somewhat as designated by the reference numeral 9. In my opinion this is an advantage in that it tends 45 to coöperate with the tongues to the end of fixing the strap with the greatest degree of security. The purpose in reinforcing the prong-like tongues is obvious, while the purpose of reinforcing them part way, that is, 50 not as far as the point, is to cause a predetermined extent (as shown approximately the entire point) to become upset and therefore clenched against the opposite or inner side of the box. The reinforced portion of the 55 tongue is best made to equal in measurement the thickness of the box material as clearly seen in Figs. VII and IX. It was this idea which constituted one of the features of my patent hereinbefore identified. Continuous 60 lengths of strap iron embodying my invention may be caused to successively puncture and clench a continuous sheet of flexible box material at a single operation by passing between rollers. In this wise a stock 65 sheet may be scored up and reinforced in

the flat, and later cut and formed as required. These two stages of preparatory operations are shown in Figs. II and III.

The modification shown in Fig. X depicts the result effected by employing perfectly 70 mated dies, the junction of the continuous strap 10, and any one of its tongues 11 being substantially right angled.

The modification illustrated by Figs. XI to XIII inclusive involves an inversion of 75 projection of the tongue stiffening rib. According to this form the strap 12 is formed with upwardly projecting corrugations 13, and downwardly punched tongues 14 having ribs 15 projecting in a direction opposite 80 to that of the ribs 8 seen in Fig. VIII.

The final modification with which Figs. XIV and XV have to do discloses the simplest form in which my invention may be practised with less though sufficient effectiveness. In this modification both the strap 16 and the pointed tongue 17 are flat.

It may not be amiss to particularly state that strap iron embodying my invention may be used with equal efficacy to bind 90 wooden boxes of rather thin veneer. When so employed the same must be applied by successive hammering over each of the prongs.

It should also be understood that the nails 95 which are shown in Fig. I are by no means indispensable because if the strap iron is not scored up with the fiber board prior to enveloping the wooden frames the prong-like tongues may themselves be caused to 100 penetrate not only through the fiber board, but also into the wooden frames.

Fig. XVI shows the incidental facility afforded by my invention for securing together the ends of one particular encircling 105 strip. This can be accomplished by causing the last of the tongues at one end to enter and become compressed relatively to the last opening in the other end. It is apparent that in the case of certain articles to be 110 shipped this facility permits of a quick opening closure without necessitating injury to the ends of the binding straps or to the upper edge of the box or its cover.

I claim:

1. A contrivance of the character described comprising a metal strap fashioned with a plurality of stiffening ribs, said strap also provided with tongues struck-out from said ribs.

2. A contrivance of the character described comprising a metal strap fashioned with a plurality of longitudinally aligned stiffening ribs, and with struck-out pointed tongues having reinforcing projections forming continuations of said ribs respectively.

3. A contrivance of the character described comprising a box forming structure including side and end members fitted together and a metal reinforcing strap conforming to 130

and enveloping said box, said strap being provided with integral pointed tongues and stiffening ribs alternately projecting longitudinally therewith, said tongues piercing said box, and furthermore clenched interiorly.

4. A contrivance of the character described comprising a box forming structure including an integral blank of fiber board shaped to form the sides of the box, a partition member fitted thereto, and a metal reinforcing strap conforming to and enveloping said

board at said partition, said strap being provided with ribs and with struck-out pointed tongues forming continuations of said ribs, said tongues piercing both said board and said partition.

Signed by me, this 5th day of March, 1915.

JOHN N. HAHN.
